HOOD LATCH

Stephen De Orlow, Jackson, Mich., assignor to
 General Motors Corporation, Detroit, Mich., a
 corporation of Delaware

Application January 10, 1941, Serial No. 373,929

2 Claims. (Cl. 292—306)

This invention relates to latches used to hold down the hinged door of the hood of an automotive vehicle.

The specific novelty of the invention resides in retaining a pilot pin on the hood either by means of a hardened pawl which grips into the side of the pilot pin, or by means of a wedging roller. The pilot pin is rotatable and a flat thereon may be caused to mate with the pawl or with the roller to render the pawl or the roller inactive to enable the pin to be withdrawn and to enable the hood to be raised. The pin is turnable by means of a suitable linkage operable from the usual ornament at the front of the hood door.

On the drawings

Figure 1 is a side view of a part of an automotive vehicle showing the invention applied and showing the hood door in raised position in dotted outline.

Figure 2 is a transverse sectional view through the hood and hood door showing the pilot pin and the manner in which it is retained in latched position. The dotted outline shows the position of the pawl when the flat on the pin mates with the pawl.

Figures 3 and 4 are sections on the lines 3—3 and 4—4 of Figure 2. The dotted outline in Figure 3 shows the position of the parts when the flat mates with the pawl.

Figure 5 is a sectional view showing the detail of the linkage which operates the pilot pin.

Figure 6 is a plan view of a part of the ornament showing the stop to limit the movement of the ornament.

Figure 7 is a view similar to Figure 2 of a modification.

Figures 8 and 9 are sections on lines 8—8 and 9—9 of Figure 7.

Referring to the drawings, the numeral 2 indicates an automotive vehicle as a whole. The vehicle has the front door 4 with the window 6 therein. The usual V-shaped windshield is indicated at 8 and the cowl at 10. The stationary hood side is indicated at 12 and the usual grille in front of the radiator is indicated at 14. The hood door 16 is of the alligator type and is hinged at its rear end by means of the hinges 18. An ornament 20 of any suitable type is positioned at the front end 22 of the hood door 16.

Under the front end 22 of the hood door, the hood has secured thereto a transverse pan or plate 24 and this plate is provided with an upwardly projecting protuberance 26 and also has a bracket 28 secured thereto by means of the

ears 30 and 32 and the rivets 34. One end of the bracket is suitably shaped to form what may be termed an opening 36 for reception of a pilot pin 38. The other end of the bracket is formed with upstanding ears 40 and between the ears a pin 42 is secured. On the pin there are turnably mounted the bearing parts 44 of a hardened steel pawl 46 the inner edge 48 of which is sharp. In the position of the pin 38 shown in Figure 2 the pawl engages in the side of the pin to hold it in the position shown. A suitably shaped coil spring 50 is positioned around the pin 42 and has its ends 52 in contact with the plate 24 and the pawl 46 and constantly urges the pawl to the dotted line position shown in Figure 2.

At the top of the opening 36 a wear member or stamping 54 is positioned and this stamping has an oval-shaped opening as is best seen in Figure 4.

At the underside of the front part 22 of the hood door there is a transverse plate 56 to which there is secured the coil spring 58. One end of the spring is threaded through an opening 60 in the plate 56, and a finger 62 bent from the plate is pressed onto the end of the coil spring to hold it in place. The bottom end of the coil spring 58 fits over the protuberance 26. The spring serves as an anti-rattle member and also acts slightly to raise the hood when the pawl 46 is released from the pin 38.

The pin 38 has a pointed end 64 to guide it into the opening in the stamping 54. The pin is also provided with a flat 66 which is adapted at times to mate with the pawl 46 to render the pawl inactive. The dotted line position of the parts in Figures 2 and 4 shows the pin 38 rotated to cause the flat 66 to mate with the sharp edge 48 of the pawl, and when the flat 66 and the pawl 46 mate the pawl will be out of engagement with the pin and enable the pin 38 to be withdrawn from the opening 36 in the bracket 28.

The transverse plate 56 is provided with an opening 68 through which there extends the neck 70 of a stamping 72. The neck 70 acts as a bearing for the bearing part 73 of the pin 38. The stamping 72 has a bottom flange which fits on the underside of the plate 56 and is secured thereto by means of the rivets 74. A shoulder 76 on the pin 38 abuts against the underside of the flange on the stamping 72.

The upper end of the pin 38 is reduced as indicated at 78 and the reduced end has a collar 80 fastened thereto by means of a pin 82. To the other end of the collar 80 there is secured the shaft 84 of a linkage indicated as a whole at

86 (see Figure 5). The upper end of the shaft 84 is mounted in a bearing 88 in a bracket 90 secured to the front end 22 of the hood door 16. An arm 92 has at one end an eye 94 rigidly secured to the shaft 84, and into an eye 96 at the other end there is secured the hook end 98 of a link 100. The other end of the link is turned at right angles and is received in an eye 104 of an arm 106, the end 108 of which is rigidly secured to the shaft 110, mounted in a bearing 112 formed in a fixture 114 secured to the top of the front end 22 of the hood door 16. The end of the shaft 110 is perfectly polygonal and is suitably secured to the ornament 20. The ornament 20 is turnable to rotate the shaft 110. A coil spring 115 is positioned around the shaft 110 and has one end 116 hooked around the arm 106 and the other end 118 positioned in a recess in the fixture 114. The spring 115 always urges the parts to the closed or latched position as shown in Figures 2 and 4.

Referring to Figure 6, it will be seen that the end of the ornament 20 has a beveled end 120 which mates with a beveled end 122 on the fixture 114. The structure of the edges 120, 122 will limit the movement of the ornament and when the parts are in engagement as shown in Figure 6, the ornament will be in its normal position and the hood door 16 latched.

The operation of the structure is as follows: The latched position of the parts is shown in Figures 2 and 4. If the operator desires to raise the hood he will grasp the ornament 20 and rotate it to cause the shaft 110 to move the linkage. This movement will be communicated by the arm 106 to the link 100, to the arm 92, and then to the shaft 84. This movement will rotate the pin 38 and cause the flat 66 thereon to mate with the edge 48 of the pawl 46. When the flat 66 mates with the edge 48 the pawl edge will be inactive or out of contact with the pin. The spring 58 will then cause the hood door slightly to be raised and by placing the fingers underneath the edge of the front end 22 of the door, the door may be raised. After the pin 38 is out of engagement with the pawl 46 the ornament 20 may be returned to its normal position as shown in Figure 1. When the operator closes the hood door the pointed end 64 of the pilot pin will enter the opening in the stamping 54 and the opening 36 in the bracket 28. Due to the fact that the pawl 46 may move on its bearings 44 the pin will push the pawl to the full line position shown in Figure 2 and thereafter any effort to raise the hood will now be resisted by the pawl because the sharp edge 48 will dig into the side of the pin 38.

In Figures 7, 8, and 9, a modification of the structure is shown. The pin 38' is essentially the same but is slightly more elongated. The bracket 28' is shaped somewhat differently and the stamping 54' also has a different shape, but parts 28' and 54' are in the same relative position. Instead of the pawl 46 of Figure 2 a roller 46' is used. This roller is mounted on a bracket 124 pivoted by means of the pin 126 to the ears 40' on the bracket 28'. A coil spring 127 has one end positioned against the stamping 54' and the other end in an opening 128 in the bracket 124 and always urges the right hand end (Figures 7 and 9) of the bracket 124 in a downward position and the opposite end of the bracket in an upward direction. The pawl 46' has end trunnions 130 journaled in the ends of the bracket 124 and these journals travel in slots 132 formed

in the bracket 28'. In the position of the parts shown in Figure 7, the hood door is in latched position, and any effort to raise the hood door will only cause a greater wedging between the roller 46' and the side of the pilot pin 38'.

The pilot pin 38' has a flat 66 thereon and by rotating the pin by the linkage mechanism 86 shown in Figure 5, the flat 66 may be caused to mate with the roller and when they are in mating position the roller 46' is inactive or can no longer hold the pin in position. The hood door may then be raised.

A spring 140 of the rat trap type has one end 142 secured by means of a clip 146 to the plate 24 while the other end 148 is formed into a loop and is free and presses against the underside of the flange 72 of the stamping 70 when the hood door is in lowered position. When the pin 38' is rotated to cause the flat 66 to mate with the roller 46' so that the hood door may be raised, the spring 140 presses upwardly on the hood door and tends to raise it slightly so that the fingers of the operator may be placed under the door to raise it. The spring 140 also functions to prevent rattle of the parts.

If desired, the bracket 124 may be omitted and a coil spring, or coil springs, placed under the roller 46' constantly to urge it in an upward direction. Or, instead of a roller urged upwardly by coil springs, a latch with a sharp lip may be used. Both the roller and the latch would be provided with trunnions riding in inclined slots.

Instead of the linkage 86, an arm may be used and have its end extend through the grille 14. By either pulling the arm or moving it laterally, the pins 38 or 38' can be caused to turn.

I claim:

1. A latch for a door of a hood or the like of an automotive vehicle comprising a bracket having means for mounting it on the hood and an upstanding portion, a pilot pin, means for turnably mounting said pin on said door, means for turning said pin, said upstanding portion of the bracket having an opening adapted to receive said pin and being formed with parallel spaced upstanding ears, and a rigid pawl pivotally mounted on and between said ears and having a sharp edge which is adapted to project into said opening, said pawl being biased so that said sharp edge constantly tends to project into said opening, said pin having a substantially smooth side wall portion for engagement by the sharp edge of said pawl when the pin is turned into its operative position for locking said door, said pin also having a recessed side portion arranged for mating with the sharp edge of said pawl so as to prevent engagement of the pin by said sharp edge when the pin is turned into its inoperative position to enable withdrawal of the pin from said opening, and the side wall of said opening opposite said pawl providing a firm lateral support for said pin when it is engaged by the sharp edge of said pawl.

2. A latch for a door of an automotive vehicle, said latch comprising a sheet metal bracket having a base portion for mounting it on the vehicle and spaced upstanding ears bent from said base portion, a pilot pin, means for turnably mounting said pin on said door, means operable from the exterior of the vehicle for turning said pin, said bracket having an upstanding portion formed with an opening adapted to receive said pin when said door is in its closed position, a rigid pawl pivotally mounted on and between said ears and having a sharp edge which is adapted

to project into said opening, and a spring biasing said pawl so that said sharp edge constantly tends to project into said opening, the major side wall portion of said pin being substantially smooth and cylindrical and a minor side wall portion thereof being flat and recessed relative to said major portion, said major portion being adapted to be engaged by the sharp edge of said pawl when the pin is turned into its operative position for locking the door in its closed position, said minor portion of the pin being ar-

10

5 ranged for mating with the sharp edge of said pawl so as to prevent engagement of the pin by said sharp edge when the pin is turned into its inoperative position to enable withdrawal of the pin from said opening and consequently opening of said door, and the side wall of said opening opposite said pawl providing a firm lateral support for said pin when it is engaged by the sharp edge of said pawl.

STEPHEN DE ORLOW.
